(57) **CLAIM**

The ornamental design for a tire tread, as shown and described.

DESCRIPTION

FIG. 1 is a front left side perspective view for a tire tread, showing my new design, it being understood that the tread pattern repeats circumferentially throughout the outer circumference and shoulder of a tire, the opposite side perspective view being identical thereto;

FIG. 2 is a front elevational view of FIG. 1 thereof, the rear elevational, top plan and bottom plan view being a mirror image; and,

FIG. 3 is a left side elevational view of FIG. 1 thereof, the right side elevational view being a mirror image.
